UNITED STATES PATENT OFFICE.

MILTON O. REEVES, OF COLUMBUS, INDIANA, ASSIGNOR TO REEVES PULLEY COMPANY, OF COLUMBUS, INDIANA, A CORPORATION OF INDIANA.

GRINDING-MACHINE.

1,264,129.

Specification of Letters Patent. Patented Apr. 23, 1918.

Application filed April 23, 1917. Serial No. 165,049.

To all whom it may concern:

Be it known that I, MILTON O. REEVES, a citizen of the United States, residing at Columbus, in the county of Bartholomew and State of Indiana, have invented a new and useful Grinding-Machine, of which the following is a specification.

The object of my invention is to produce a simple and efficient machine for accurately grinding cylindrical objects, such as rollers for roller bearings, at small expense.

The accompanying drawings illustrate my invention. Figure 1 is a plan of a machine embodying my invention; Fig. 2 a front elevation; Fig. 3 a side elevation; Fig. 4 a section on line 4—4 of Fig. 5; Fig. 5 a section on line 5—5 of Fig. 4; Fig. 6 a plan of a modified form of machine; and Fig. 7 a plan of another modification.

In the drawings, 10 indicates a main frame carrying a longitudinally adjustable cross head 11, mounted in suitable guides 12 in the frame 10, and readily longitudinally shiftable by means of a hand lever 13, spring 14, pinion 15 and rack 16. Movement of the cross head in one direction is limited adjustably by a temper screw 17. Journaled in cross head 11, parallel with the movement of the cross head, is a shaft 21 which carries a crown wheel 22 at one end. By crown wheel, I mean a ring having an active face at an angle, preferably closely approximating 90°, to the axis of the wheel. This crown wheel is not necessarily an abrading element, but it is much more convenient that its active face should be of a standard abrading material of desired texture, such that it may control the speed of rotation of the article to be ground.

Mounted upon frame 10 beyond the propeller wheel 22, is a head 25, in which is journaled a shaft 26 which lies substantially at right angles to the axis of the shaft 21, and carries at one end a grinding wheel 27, the circumferential edge of which is arranged closely adjacent the active crown face of the wheel 22. Head 25 is carried upon the upper end of a cross head 28 which may be vertically adjusted by adjusting screw 29 and, in order that the vertical angle of shaft 26 may be adjusted, one of its bearings 30 is pivoted at 31 upon head 25, while the other bearing 32 is supported by a wedge 33 which may be adjusted by a temper screw 34, so as to tilt shaft 26 in a vertical plane.

Bearing 32 after adjustment is clamped in place by clamping screws 35. Any other suitable means may be provided for adjusting the vertical angle of the shaft 26.

Mounted between the adjacent faces of wheels 27 and 22, is a work-supporting platform 36, which is carried upon the upper end of a cross head 37, mounted in a guide 38 and vertically adjustable by means of an adjusting screw 39. Guide 38 is carried by a horizontally movable cross head 40, mounted in suitable guides 41, and horizontally adjustable by the adjusting screw 42, the arrangement being such that platform 36 may be readily adjusted both horizontally and vertically.

In the form shown in Figs. 1-5, inclusive, crown wheel 22 is rotated at a comparatively slow speed in the direction indicated by the arrows, and wheel 27 is rotated at a very much higher speed in the direction indicated by the arrows. Shaft 26 may be adjusted either to lie in a plane parallel with the plane of platform 36, or may be tilted vertically in either direction from this position. With the propeller wheel rotating in the direction indicated by the arrows, platform 36 will be adjusted so as to bring the axis of the article 43 to be ground, practically into the plane of the axis of shaft 26 at the middle of the active face of wheel 27, and if the axis of shaft 26 is parallel to the platform 36, the coaction of the two wheels 22 and 27 upon the interposed article 43, will be such as to rotate said article upon its own axis, and to feed the same slowly axially between the two wheels 22 and 27 and toward the axis of shaft 21. This axial movement of the article 43 may be retarded by adjusting the wheel-end of shaft 26 upwardly. An adjustment of the angle of shaft 26 in the opposite direction will accelerate the axial movement of article 43. Variation of the angle of axis 26 from parallelism with platform 36 will, of course, require a vertical adjustment of head 25 until the full radius of wheel 27 is brought substantially opposite the axis of article 43, and this variation of the axis of shaft 26 from parallelism with platform 36 will either require, or result in, a slight concavity of the circumferential surface of wheel 27, this being indicated in a much exaggerated manner in the drawings. It will, of course, be understood that the actual divergence of shaft 110

26 from parallelism with the plane of platform 36 is not great, and that the actual concavity of the active surface of wheel 27 would, in many instances, be hardly perceptible to the eye.

5 I have found in practice that the rotation and axial feeding of the article 43 is largely controlled by wheel 22, which I have called the propeller wheel, while the grinding operation is accomplished by the more rapidly moving wheel 27.

10 In the form shown in Fig. 6, shaft 51 carries the propeller wheel 52 and is supported in bearings which are carried by cross head 53 adjustable, by a screw 54, laterally at right angles to the axis of the shaft. Shaft 55 is substantially parallel with shaft 51, or at some defined horizontal angle relative thereto, and carries a grinding wheel 56. 15 The two wheels 52 and 56 are set so as to have their circumferential edges in co-operative relationship. The shaft 55 is carried in bearings supported by a head 57 which is vertically and angularly adjustable in a 20 manner similar to head 25 and bearings 30, 32. In this figure, the circumferential surface of wheel 56 is shown as concaved, to an exaggerated extent, as a result of adjustment of the axis of shaft 55 vertically 25 30 out of parallelism with shaft 51.

35 It will be readily understood that, in this form, the circumferential surfaces of either, or both, wheels 52 and 56 may be conical frustums. A work-supporting platform 36 is mounted between the most adjacent portions of the two wheels.

40 In Fig. 7, I have indicated, in a fragmentary manner, a possible arrangement of two crown wheels 61 and 62, arranged to overlap at their crown edges, at one point, with a work-supporting platform 63 between them at this point of adjacency. The two wheels will be rotated in the same direction and at different speeds, the slower wheel 45 serving as a propeller, while the faster wheel operates as a grinder.

50 It should also be understood that the relative axial movement of the article 43 may be controlled both as to amount and direction by vertical adjustment of the platform 36 relative to the axis of the propeller wheel 22 and its direction of rotation. It is preferable that the grinding wheel move downwardly adjacent the platform 36 and the 55 propeller must therefore move upwardly adjacent the platform. If the axis of the article 43 be above the horizontal axis of the propeller wheel 42, and, of course, not radial, the axial movement of article 43 will be toward the axis of the propeller and the speed 60 of this movement will be increased as platform 36 is raised. If the axis of article 43 is radial, there will be no axial movement of the article, and if the axis of the article 65 is carried below the axis of the propeller,

the axial movement of the article will be outwardly. In all cases, however, the axis of the article 43 should be so arranged, by adjustment of platform 36, that the radius of wheel 27 through its active surface will 70 intersect the axis of article 43. It will be readily understood, therefore, that either one of wheels 22 and 27 will be made vertically adjustable, whichever is found to be most convenient for other structural reasons. 75

I claim as my invention:

1. In a grinding machine, the combination of a rotary propeller wheel having an active crown face, a grinder wheel having an active circumferential face arranged to coöperate with the crown face of the propeller wheel, a work-supporting member arranged to support a cylindrical object between the adjacent active faces of the propeller wheel and grinder, means for adjusting the relation between the propeller wheel and work-support to offset from a radius the contact line between the propeller and the object to be ground and to maintain the axis of the article to be ground substantially upon the radius of the grinding wheel passing through the grinding line of contact, and means for setting the axis of the grinder and the work support out of parallelism.

2. In a grinding machine, the combination of a rotary propeller wheel having an active crown face, a grinder wheel having an active circumferential face arranged to coöperate with the crown face of the propeller wheel, a work-supporting member arranged to support a cylindrical object between the adjacent active faces of the propeller wheel and grinder, and means for adjusting the relation between the propeller wheel and work-support to offset from a radius the contact line between the propeller and the object to be ground and to maintain the axis of the article to be ground substantially upon the radius of the grinding wheel passing through the grinding line of contact.

3. In a grinding machine, the combination of a rotary propeller wheel having an active crown face, a grinder wheel having an active circumferential face arranged to coöperate with the crown face of the propeller wheel, a work-supporting member arranged to support a cylindrical object between the adjacent active faces of the propeller wheel and grinder, and means for setting the axis of the grinder and the work support out of parallelism.

4. In a grinding machine, the combination of a rotary propeller wheel having an active crown face, a grinder wheel having an active circumferential face arranged to coöperate with the crown face of the propeller wheel, a work-supporting member arranged to support a cylindrical object be-

3

- between the adjacent active faces of the propeller wheel and grinder, means for vertically adjusting the axis of the grinding wheel, means for vertically adjusting the 5 work support and means for adjusting the vertical angle of the axis of the grinder relative to the plane of the work support.

5. In a grinding machine, the combination of a rotary propeller wheel having an active crown face, a grinder wheel having an active circumferential face arranged to cooperate with the crown face of the propeller wheel, a work-supporting member arranged to support a cylindrical object between the adjacent active faces of the propeller wheel and grinder, means for vertically adjusting the axis of the grinding wheel, and means for vertically adjusting the work support.

10. In a grinding machine, the combination of a rotatable propeller wheel having an active crown face, a rotatable grinding wheel having an active circumferential face arranged to cooperate with the crown face of the propeller wheel, a work-supporting member arranged to support a cylindrical object between the adjacent active faces of the propeller wheel and grinder, means for vertically adjusting the axis of the grinding wheel, and means for vertically adjusting the work support.

15. In a grinding machine, the combination of a rotatable propeller element and a rotatable grinding wheel having an active circumferential face arranged adjacent the propeller element to form a throat for the reception of a cylindrical object to be ground, means for supporting such cylindrical object in said throat, and means for adjusting the angle of the axis of the grinding wheel relative to the plane of the work support.

20. In a grinding machine, the combination of a rotatable propeller element and a rotatable grinding wheel having an active circumferential face arranged adjacent the propeller element to form a throat for the reception of a cylindrical object to be ground, means for supporting such cylindrical object in said throat, and means for adjusting the angle of the axis of the grinding wheel relative to the plane of the work support.

25. In a grinding machine, the combination of a rotatable propeller element and a rotatable grinding wheel having an active circumferential face arranged adjacent the propeller element to form a throat for the reception of a cylindrical object to be ground, means for supporting such cylindrical object in said throat, and means for adjusting the angle of the axis of the grinding wheel relative to the plane of the work support.

30. In a grinding machine, the combination of a rotatable propeller element and a rotatable grinding wheel arranged adjacent the propeller element to form a throat for the reception of a cylindrical object to be ground, means for supporting such cylindrical object in said throat, and means for adjusting the angle of the axis of the grinding wheel relative to the plane of the work support.

35. In a grinding machine, the combination of a rotatable propeller element and a rotatable grinding wheel arranged adjacent the propeller element to form a throat for the reception of a cylindrical object to be ground, means for supporting such cylindrical object in said throat, and means for adjusting the angle of the axis of the grinding wheel relative to the plane of the work support.

40. In a grinding machine, the combination of a rotary propeller wheel having an active crown face, a grinder wheel having an active circumferential face arranged to cooperate with the crown face of the propeller wheel, a work-supporting member arranged to support a cylindrical object between the adjacent faces of the propeller wheel and grinder to produce a non-radial contact between the crown face of the propeller and the cylindrical object.

45. In a grinding machine, the combination of a rotatable propeller wheel having an active crown face, and a rotatable grinding wheel having an active circumferential face arranged adjacent the propeller wheel to form a throat for the reception of a cylindrical object to be ground, means for supporting such cylindrical object in said throat, and means for adjusting the relation between the work-support and propeller to vary the lateral offset of the axis of the article to be ground relative to the active radius of the propeller wheel.

50. In a grinding machine, the combination of a rotatable propeller element and a rotatable grinding wheel having an active circumferential face arranged adjacent the propeller element to form a throat for the reception of a cylindrical object to be ground, means for supporting such cylindrical object in said throat, and means for adjusting the relation between the work support and propeller to vary the lateral offset of the axis of the article to be ground relative to the radius of the propeller element.

55. In witness whereof, I have hereunto set my hand at Indianapolis, Indiana, this twenty-sixth day of April, A. D. one thousand nine hundred and seventeen.

MILTON O. REEVES
